ARM REST FOR SOFA OR CHAIR

Gordon Hrach, Bedford, Ohio, assignor to The B. L. Marble Chair Company, Bedford, Ohio, a corporation of Ohio

Application April 30, 1957, Serial No. 45,951

Term of patent 7 years

(Cl. D15—11)

Fig. 1.

Fig. 2.

Fig. 3.

Fig. 1 is a side perspective view of an arm rest for a sofa or chair, showing my new design;

Fig. 2 is a side elevational view; and

Fig. 3 is an end elevational view thereof.

The dotted line showing in the drawing is for illustrative purposes only.

The dominant features of my design are shown in full lines.

I claim:

The ornamental design for an arm rest for a sofa or chair, as shown and described.
